[57] CLAIM

The ornamental and original design for an extensible support for hanging potted plants, substantially as shown and described.

DESCRIPTION

FIG. 1 is a top plan view of an extensible support for hanging potted plants showing my new design;
FIG. 2 is an end elevational view thereof, with the extensible member omitted for clarity of illustration;
FIG. 3 is a side elevational view of FIG. 2;
FIG. 4 is a side elevational view showing the side opposite that shown in FIG. 3, with the extensible member in the extended positions;
FIG. 5 is a bottom plan view of FIG. 2.
